**Islyn Thomas, Newark, N. J., assignor to Thomas
Manufacturing Corp., Newark, N. J.**

Application April 8, 1948, Serial No. 145,600

Term of patent 14 years

(Cl. D34—15)

To all whom it may concern:

Be it known that I, Islyn Thomas, a citizen of the United States and resident of the city of Newark, county of Essex, and State of New Jersey, have invented a new, original, and ornamental Design for a Toy Swing, of which the following is a specification, reference being had to the accompanying drawings, forming part thereof.

Fig. 1 is a front elevation of the toy swing, showing my new design.

Fig. 2 is a side elevation thereof.

The side of the toy swing not shown in the same as the side shown and the rear of the toy swing is substantially the same as the front

thereof, the seat of the swing being closed at the rear.

I claim:

The ornamental design for a toy swing, substantially as shown and described.

ISLYN THOMAS.
